UNITED STATES PATENT OFFICE

IRVING PERCY SIMONSEN AND ARCH C. HUSTON, OF LOS ANGELES, CALIFORNIA; SAID
SIMONSEN ASSIGNOR TO SAID HUSTON

MAGNETIC DIE

Application filed August 4, 1930. Serial No. 473,112.

This invention has reference to dies, typically of the character used for cutting and shaping sheet metal pieces such as bottoms for paper cans and the like, and is concerned particularly with improvements for effecting the disengagement or removal of the shaped piece from the die after operation on the piece has been completed.

In cutting and shaping pieces from sheet metal stock by use of the present type of die, the stock is placed between a pair of dies which are caused to move relatively toward and then away from each other in a cutting and forming operation.

In common types of sheet metal dies of which we are aware, the shaped piece, after being cut and formed from the stock by the dies and as the latter move apart, is carried by one of the dies by reason of its frictional engagement therewith. The piece is then disengaged from the die and removed prior to the subsequent operation.

It may be stated that this method of causing the shaped piece to become disengaged from the dies has the disadvantage that frictional engagement between the work and the carrying die cannot alone be relied upon to insure that the work will always be disengaged from the other die. Such factors as wearing of the die parts and variation in the thickness of the sheet metal stock may cause failure of the parts to function in the manner intended, with the result that operations are interrupted or slowed down due to the necessity for manual or gravity manipulation.

These difficulties are overcome in accordance with the invention by the provision of a magnetized die adapted to retain the shaped piece as the dies move relatively apart, in combination with a simple mechanism for automatically disengaging the work from the magnetized die. By thus causing the work to be held by the carrying die by magnetic attraction rather than by frictional engagement, it is assured that the operation of disengaging the work from the die will take place in the proper manner regardless of wear on the parts or variations in the thickness of the stock, thus obviating the necessity for

frequent attention on the part of the operator, as has commonly been the case.

For purposes of describing the invention, I have shown it to be embodied in a typical form of combination die for forming metal bottoms for tubular paper cans. It is to be understood, however, that in its broader aspects the invention is not to be regarded as limited to the particular type of die shown herein, since the invention may be embodied in numerous forms of dies without departure from its intended spirit and scope.

Reference is had throughout the following detailed description to the accompanying drawing in which

Figure 1 is a front elevational view showing a typical form of die press embodying the invention;

Fig. 2 is an enlarged fragmentary section taken through the die parts and showing the work to be pressed between the dies; and

Fig. 3 is a view similar to Fig. 2 but showing the dies in work releasing position.

The invention contemplates the use of the hereinafter described die parts in any suitable form or design of press. However, as a typical construction, I show a press comprising a bed 10 and an upper arched supporting frame 11 on which is mounted the upper vertical movable die and the operating mechanism for that die. The lower stationary die generally indicated at 12 is supported on bed 10 and comprises an annular die block 13 having a cutting edge at 14 and having also a bottom counter-bore 15 between which and the upper bore 16 is presented an annular shoulder 17. Within the die block 13 is a stationary block 18 having a cylindrically shaped upper portion annularly spaced from the walls of bores 15 and 16. A vertically movable lifting ring or pressure pad 19 is placed within the annular space between blocks 13 and 18, the pressure pad being movable between the limits indicated in Figs. 2 and 3, the latter indicating the normal upper position of the lifting ring in which its upward movement is arrested by the engagement of flange 19a with shoulder 17 in the outer die block. In this position the upper end of the pressure pad is substantially even

with the top surface of block 13. The lifting ring is limited in its downward movement by the lowest position of the upper die.

Any suitable means may be employed for 5 yieldably supporting the pressure pad in its normal position. As typical of such means I show the pressure pad to be supported on vertically movable pins 22 extending through bores in the bed 10 and block 18 and terminating at their lower ends in a cross piece 23. The latter is slidably mounted on a bolt 24 carried in the bed and is yieldably supported by coil springs 25 bearing against a washer or head 26 on the lower end of the 10 bolt.

The upper magnetized die generally indicated at 27, is mounted on a vertically movable carrier or head 28 which is confined for movement in a vertical path by extensions 29 20 movable between guide pieces 30 secured to the sides of the frame 11. The head 28 is operated in its vertical reciprocating movement by connection with a shaft 32, 32a journaled in bearings 33 and driven from 25 pulley wheel 34. On the inner ends of the shaft sections 32, 32a are crank arm extensions 35 carrying eccentrically positioned intermediate portion 32b of the shaft which is connected by rods 37 with pins 39 on the 30 head 28. Thus by virtue of the eccentricity of the intermediate shaft section 32b with relation to the end portions 32, upon rotation of the shaft there is imparted to the head 28 a vertical reciprocating movement.

Depending from the head 28 is a cylindric core 40, the diameter of which may be slightly less than the diameter of the upper cylindrical portion of the inner block 18 of the lower die. Core 40 is surrounded by a 40 tubular punch block 41, the lower reduced diameter end portion 41a of which projects somewhat below the lower end of the core and is adapted to register with the upper end of the pressure pad 19, or in other words the 45 annular space between blocks 13 and 18. Placed within the upper interior of the punch 41 and surrounding the core 40 is an electric coil 42 having lead wires 43 leading to a suitable source of current, not shown. The core 50 40 thus provides an electrode magnet, the purpose of which will presently appear. An air gap is provided at 40a between the lower ends of the core 40 and the punch 41 in order to insulate the magnetized core from the 55 punch block to give them opposite polarity.

A pair of what may be termed knock-out pins 43, of brass or other suitable non-magnetic material, is inserted within bores extending longitudinally through the head 28 60 and core 40, the pins 43 being vertically movable relative to the head assembly. The pins are connected at their upper ends by a cross piece 44 having an integral depending guide lug 45 working within bore 46 in the upper 65 end of the head. The knock-out pin assembly

is yieldably supported by coil springs 47 which normally, that is when the head is in its lower position shown in Fig. 2, support the pins in such position that their lower ends are raised to a point even with or above 70 the lower end of the core. Upon upward movement of the head to the position of Fig. 3, the upper end of the guide lug 45 projecting above the cross piece 44 is brought into engagement with a stationary stop or abutment 48 depending from the upper portion of the frame 11, so as to arrest further upward movement of the knockout pins with the head and thereby cause them to project below the lower end of the core as shown in 80 Fig. 3. The stop 48 may be suitably curved longitudinally so as to clear the drive shaft.

In operation, the sheet metal stock 50 is placed between the dies with the parts in the positions of Fig. 3. Upon downward movement of the head to the position of Fig. 2, a circular bottom 50a is cut from the sheet metal stock by the shearing action of the upper die in passing into the lower die bore 16. Upon engagement of the stock by 90 the lower end of the upper die, the pressure ring 19 is displaced downwardly to the limiting position of Figure 2, whereupon the cap is bent around the upper end of the block 18 and formed in the manner indicated. 95 As previously mentioned, this particular form of tin part is suitable for application by subsequent operations to tubular paper cans and similar containers. In the usual die mechanism of this character the frictional 100 engagement of the tin part by the upper die is relied upon to raise the shaped cap out of the lower die and to a position such that it may be taken from between the dies. It will be readily apparent, however, that as the die parts become worn and in the event of substantial variation in the thickness of the stock, the upper die may fail to so pick up the shaped part in the manner intended, in 105 which event manual operation or gravity are 110 relied on to displace the cap.

The invention obviates this difficulty by the provision of a magnetic pick-up for the tin part and of means for automatically releasing the tin part from the die against the magnetic attraction holding it thereto. Thus upon upward movement of the head, the tin part is held within the upper die by the magnetized core and punch until such time as the cap is disengaged by the knock-out pins. At 115 the point of engagement of the knock-out pin assembly with stop 48, the pins 43 are caused to project below the lower end of the core and to disengage the tin part from the upper die, as will be readily understood. It 120 may be mentioned that in practice the dies will be positioned on an incline, that is, the dies will be inclined with respect to the vertical, so that as the shaped cap is disengaged it will immediately fall or slide by gravity 130

to one side from between the dies and to one side of the hole punched in the stock in order that the dies may be caused to operate at a rapid rate without the necessity for manually removing each formed tin part from between them. For purposes of simplicity in illustrating the invention, the dies are not shown to be so inclined since the invention resides in the die parts themselves and the 10 operation will be readily apparent by illustrating the dies in the position shown.

I claim:

1. In a device of the character described, a pair of dies movable relatively together 15 and apart for operating on a paramagnetic work-piece placed therebetween, one of said dies being magnetized so that as the dies move relatively apart the magnetized die initially retains the shaped piece, and means 20 for subsequently automatically disengaging said piece from the magnetized die upon further separating movement of said dies.
2. In a device of the character described, a lower die, a vertically movable head above 25 said lower die, an upper magnetized die comprising a magnetized core carried on said head and movable toward and away from said lower die in the operation of shaping a paramagnetic work-piece placed therebetween, said magnetized die carrying the 30 shaped piece with it after operation thereon, means providing a stationary abutment, and a relatively vertically movable member carried by said head and extending through 35 said core, said member being adapted to engage said stationary abutment upon upward movement of the head, a predetermined distance and to disengage the shaped piece from said upper magnetized die.
3. In a device of the type described for shaping sheet blanks of paramagnetic material, a first die comprising a forming head surrounded by an annular groove, a second die comprising a central core portion of 45 paramagnetic material juxtaposed to the forming head of said first die, and an outer annular portion also of paramagnetic material surrounding and spaced from said core portion and juxtaposed to said annular 50 groove in the first die, yoke means of paramagnetic material joining said central and annular portions at the end remote from the die face, a magnetizing winding surrounding 55 said central core whereby the working faces of said core and annular portion constitute opposite poles of an electromagnet for powerfully attracting a work-piece of paramagnetic material positioned between the first and second dies, means for moving said 60 dies toward and away from each other, means for positively dislodging a work-piece from said second magnetic die, and means for actuating said dislodging means when said two dies have separated a predetermined distance.
4. A device as described in claim 3 in 65

which said first and second dies are positioned for relative movement toward and away from each other in a laterally inclined direction, whereby a work-piece when discharged from said magnetic die falls clear 70 of said first die.

In witness that I claim the foregoing I have hereunto subscribed my name this 29 day of July, 1930.

ARCH C. HUSTON.
IRVING PERCY SIMONSEN.
